UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPET.

Specification forming part of Design No. 11,505, dated November 11, 1879; application filed September 24, 1879.
[Term of patent 3½ years.]

to all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

Said design consists of the following elements, to wit:

First, two shields, A B, one overlapping the other. The shield A is circular, and is ornamented by sprays of leaves and flowers. The shield B is octagonal, and ornamented by diagonal and short vertical lines.

Second, the vase C, containing flowers and leaves.

Third, floral designs representing different kinds of flowers, leaves, mosses, cat-tails, &c., disposed so as to nearly cover the ground of the carpet around the shields A B and vases C.

I claim—

The design for a carpet, consisting of the shields A and B, vases C, and surrounding floral designs.

In testimony whereof I have signed my name to this specification, in the presence of two subscribing witnesses, this 22d day of September, 1879.

THOMAS J. STEARNS.
